LOUDSPEAKER SYSTEM

Max Appenzeller, Berlin, Germany, assignor to
 Telefunken Gesellschaft für Drahtlose Tele-
 graphie m. b. H., Berlin, Germany, a corpora-
 tion of Germany

Application November 9, 1940, Serial No. 364,957
 In Germany August 15, 1939

6 Claims. (Cl. 179—2)

Establishments of more than average size, restaurants, assembly halls, etc., are often equipped with loudspeakers, with one or more small-sized units being installed in the various rooms. Such loudspeaker installation serves to distribute news of all kinds, for instance, for reception of broadcast programs, reproduction and repetition of general instructions, and the like. Loudspeaker installations of this nature covering the entire plant or establishment offer a number of advantages. For instance, works addresses and similar activities are feasible immediately practically without any preparation, with only a minimum loss of working time.

Over and above these purposes, loudspeaker installations as here concerned, where introduced and adopted on a more general and comprehensive scale, very soon demonstrated their utility for special problems of an organizational and technical nature. For instance, loudspeaker installations were used for the transmission of air caution and alarm signals (preliminary alert, warning and restoration of normal condition or all clear signal), of instructions and orders of the air warden, fire alarm signals, stop-work signals and search for lost persons.

Such uses to which loudspeaker installations were put made it necessary to make conditions so that from the central office certain signals should be transmissible to the loudspeaker at all times, even when the latter is disconnected from the transmission line itself. This according to the invention is insured by connecting with the various loudspeaker units two transformers having their primary and secondary windings arranged in series, the circuit organization being so chosen that, according to the nature of the signals to be transmitted only one transformer is operative at a given time. This condition, for instance, is insured by uniting the junction point of the two primary windings with one of the leads brought from the amplifier, while the other two terminals of the two primary windings are connected with a change-over switch designed to short-circuit during normal operations the primary winding of one transformer, and during alarm operation the primary winding of the other transformer.

The appended drawing illustrates an exemplified embodiment of the object of the invention. Associated with loudspeaker L are two transformers T¹ and T², the primaries and secondaries of which are connected in series. The primary windings are indicated by P¹ and P², the secondary windings by S¹ and S². Included in

the circuit of the primary winding P¹ is an L-type resistance pad R to control the loudspeaker volume. An amplifier mounted at the central point or station is indicated by A. The dot and dash line X serves to indicate the separation between the central station at the left and remote loudspeakers L at the right. The junction point A of the primary windings P¹ and P² is united with one of the leads, 1, brought 5 from the amplifier A. The other terminal of the primary winding P¹ is brought to the lead 2, and that of the primary winding P² of the second transformer to the lead 3. Leads 2 and 3 are connected with a change-over switch S. 10 In the position indicated by the solid lines, which corresponds to normal operation conditions, transformer T¹ is connected with the output of the amplifier A. The primary winding P² of the second transformer is short-circuited. If, then, 15 the switch S is thrown over to occupy the position indicated by the dash-lines and this occurs whenever orders, say, air protection signals or instructions of the works management are to be transmitted, the primary winding P¹ of the transformer T¹ is short-circuited and the potentials prevailing in the output circuit of the amplifier are impressed upon the primary winding P² of the second transformer. As can be seen 20 from the circuit diagram, it is immaterial which position the regulating resistance pad R occupies. In fact, the circuit brought to the primary winding P¹ may be entirely broken, as for example, by means of the switch SW (which may be an "on-off" switch) and even then the alarm signal will 25 reach the loudspeaker in full intensity.

What I claim is:

1. A signalling system comprising a three-wire transmission line, two of said wires constituting a first transmission line and being reserved for the transmission of one kind of message, the third wire and one of the first two wires constituting a second transmission line and being reserved for the transmission of another kind of message, a loudspeaker at a remote point, coupling means between each transmission line and the loudspeaker, a signal source at a central point, and control means at the central point for selectively connecting the signal source to said first or second transmission line depending upon the kind of message it is desired to be transmitted to the remote point.
2. A signalling system comprising a three-wire transmission line, two of said wires constituting a first transmission line and being reserved for the transmission of one kind of message, the third wire and one of the first two wires constituting a second transmission line and being reserved for the transmission of another kind of message, a loudspeaker at a remote point, coupling means between each transmission line and the loudspeaker, a signal source at a central point, and control means at the central point for selectively connecting the signal source to said first or second transmission line depending upon the kind of message it is desired to be transmitted to the remote point.

third wire and one of the first two wires constituting a second transmission line and being reserved for the transmission of another kind of message, a loudspeaker at a remote point, coupling means between each transmission line and the loudspeaker, an audio amplifier at a central point provided with a pair of output terminals one of which is connected to the wire common to both transmission lines, and switch means at the central point for selectively connecting the other amplifier output terminal to the remaining wire of one or the other transmission line depending upon the kind of message it is desired to be transmitted to the remote point and simultaneously short-circuiting the coupling means connected to the inoperative transmission line.

3. A loudspeaker system comprising an audio amplifier at a central point, at least one loudspeaker at a remote point, a three-wire transmission line associated with said audio amplifier, a pair of transformers the primaries and secondaries of which are connected respectively in series, connections from each wire of the transmission line to respectively the terminals of the transformer primaries, means for connecting the loudspeaker across the transformer secondaries, and switch means at the central point so constructed and arranged that in either of its two positions one of the transformer primaries is selectively short-circuited while the other primary is operative to transmit the signal from the amplifier to the loudspeaker.

4. A signalling system comprising an audio amplifier at a central point provided with a pair of output terminals, a three-wire transmission

line, one of said wires being directly connected to one of the amplifier output terminals, switch means for selectively connecting the other output terminal to the two remaining wires of the transmission line, a pair of transformers the primaries and secondaries of which are connected respectively in series, a connection from the common terminal of the primaries to the first mentioned transmission line wire, connections from the remaining terminals of the primaries to respectively the remaining transmission line wires, and a loudspeaker connected across the transformer secondaries.

5. A loudspeaker system comprising an audio amplifier at a central point, a plurality of loudspeakers one or more of which are located at one or more remote points, a transmission line interconnected between said amplifier and loudspeakers, means at the remote point individual to each loudspeaker for connecting and disconnecting the loudspeaker from the transmission line, and means at the central point for operating said loudspeakers even though the disconnecting means has been operated whereby the loudspeakers are at all times under complete control of the amplifier at the central point.

6. A loudspeaker system comprising an audio amplifier at a central point, at least one loudspeaker at a remote point, a transmission line interconnected between said amplifier and loudspeaker, a pair of transformers each having a primary and a secondary for coupling the loudspeaker to the transmission line, and switch means at the central point selectively short-circuiting one of said transformer primaries.
